BOMB SHELTER

Willard Bascom, Washington, D.C., assignor to American Home Shelters, Berkeley, Calif., a firm

Application November 29, 1957, Serial No. 48,706

Term of patent 14 years

(Cl. D13—1)

Fig. 1.

Fig. 2.

Fig. 3.

Fig. 4.

Fig. 1 is a side elevational view of a bomb shelter showing my new design.

Fig. 2 is a top plan view thereof.

Fig. 3 is a view of one end in elevation thereof.

Fig. 4 is a perspective view taken from the other end thereof.

I claim:

The ornamental design for a bomb shelter, as shown.
